UNITED STATES PATENT OFFICE

164,683

AUTOMOBILE

Albert E. Fry, Los Angeles, Calif.

Application June 20, 1949, Serial No. 3,419

Term of patent 14 years

(Cl. D14—3)

To all whom it may concern:

Be it known that I, Albert E. Fry, a citizen of the United States, residing at Los Angeles, in the county of Los Angeles and State of California, have invented a new, original, and ornamental Design for an Automobile, of which the following is a specification, reference being had to the accompanying drawing, forming part thereof, in which:

Fig. 1 is a side elevational view of an automobile, showing my new design;

Fig. 2 is a front elevational view thereof;

Fig. 3 is a rear elevational view thereof;

Fig. 4 is a top plan view thereof; and

Fig. 5 is a rear perspective view thereof.

I claim:

The ornamental design for an automobile, substantially as shown.

ALBERT E. FRY.
